UNITED STATES PATENT OFFICE.

GEORGE F. NEVIN AND JOHN GOODLAND, JR., OF BUTTE, MONTANA.

DEVICE FOR DRESSING ROCK-DRILL BITS.

Application filed May 9, 1925. Serial No. 29,190.

This invention relates to rock drill bits and more particularly to a device for dressing the same.

Rock drills are commonly provided with a central channel through which water is forced to clear away rock chips and dust. However, as is well known, the channels become frequently clogged and thereby inoperative.

10 It is an object of the invention to so form the inner end of the channel as to make it substantially non-plugging.

Another more special object is to provide simple means whereby the inner end of the 15 channel may be effectively constricted to make it non-plugging.

Another special object is the provision of a device which may be associated with a drill bit sharpening device for carrying out 20 the constricting operation.

For a clear understanding of the invention, reference is made to the accompanying drawings in which:

Figs. 1 and 2 are a section and an end 25 view, respectively, of a drill bit embodying the invention;

Fig. 3 is a more or less diagrammatic representation of an arrangement for carrying out the object of the invention;

30 Fig. 4 is an elevation, partly in section, of a tool, more particularly identified with the invention;

Fig. 5 is a sectional view on an enlarged scale of detail shown in Fig. 3; and

35 Fig. 6 is an end view of an auxiliary part shown in Figs. 3 and 5.

In Figs. 1 and 2 is represented a drill bit 10 consisting of the shank 10^a, the cutting edges 10^b and the channel 10^c. In the center 40 of the cutting surface of the bit is formed a cup depression 11 defining an annular fin 12 swaged inwardly leaving a constricted passage 12^a. As appears from the drawing, the fin 12 terminates in a relatively sharp edge which makes it practically impossible for chips and dust to be packed or wedged in the passage 12^a or for larger chips to 45 work back into the channel 10^c.

An important part of the invention is the 50 mechanism for forming the constriction just described.

In Fig. 3 is represented an arrangement including the usual chuck 13 for holding the 55 drill bit during the sharpening operation and the usual pneumatic hammer or the like 14 for operating a sharpening tool.

These elements are part of the ordinary drill bit sharpening mechanism and do not form part of the invention proper. However, the invention is specially correlated to 60 these elements so as to reduce the mechanism for providing the constriction to a practical minimum.

Between the pneumatic hammer 14 and the chuck is interposed a clamping standard 65 15 for holding a bushing 16 which acts as a bearing for the dolly 17. The dolly 17 has a cup forming end 17^a defined by a bowl-shaped depression 17^b in the center of which is a pin-like projection 17^c. The 70 dolly is made of tool steel or the like.

The operation is as follows:

The drill bit 18 is placed, while hot, in the chuck, as shown in Fig. 3, so that it just comes in contact with the countersunk 75 face of the bushing 16. Air is admitted to the pneumatic hammer and the hammer strikes against the head 17^d of the dolly. The latter is driven forward by the hammer until the shoulder formed by the head 17^d 80 comes in contact with the bushing which stops the movement of the dolly and the cupping operation is completed.

The cup-shaping portion 17^a is forced into the relatively softer steel of the drill bit 85 and swages the resulting annular fin inwardly to a relatively sharp edge while the pin shaped projection 17^c uniformly limits the movement of the fin and defines the constricted passage 12^a. 90

In practice, the operation described ordinarily follows the sharpening operation. The standard 15 may be permanently fixed in position. To carry out the sharpening operation, the dolly 17 and the bushing 16 95 are first removed and after the drill steel is sharpened, they are re-inserted to carry out the operation as above described.

The recess 19 of the dolly bushing also acts as a gauge for the rock drill bit. In 100 practice the outer surface of the cup-forming portion is slightly tapered. The dolly therefore also acts upon the drill steel to force the cutting portions 10^b outwardly into engagement with the wall of the recess 19 whereby the cutting edges are centered. It is understood that for each size of drill bit a corresponding bushing is used. 105

We claim:

1. Apparatus for constricting the mouth 110 of the central channel in a rock drill bit, including a dolly having at its working end

a circular cutting edge defining inwardly a bowl-shaped recess.

2. Apparatus for constricting the mouth of the central channel in a rock drill bit, including a dolly having at its working end a circular cutting edge defining inwardly a bowl-shaped recess, and a pin-shaped projection extending centrally from the bottom of the recess.

10 3. In a rock drill sharpening device, means for constricting the central channel in a drill rod, comprising a dolly having at its working end a circular cutting edge wedge-shaped in cross-section, the recess defined by the cutting edge having at its outer end a diameter greater than the diameter of the channel and gradually decreasing toward its bottom.

15 4. Combination according to claim 3, in which the recess in the dolly is bowl-shaped.

5. Combination according to claim 3, in-

cluding a pin-shaped projection extending centrally from the bottom of the recess.

6. Combination according to claim 3, in which the recess in the dolly is bowl-shaped 25 and including a pin-shaped projection extending centrally from the bottom of the recess.

7. Combination according to claim 3, including a bushing affording a bearing for 30 the dolly, and a standard provided with means for clamping the bushing to it.

8. Combination according to claim 3, including a bushing affording a bearing for the dolly and provided at one end with a 35 drill bit receiving recess, and a standard provided with means for clamping the bushing to it.

In testimony whereof, we affix our signatures.

GEORGE F. NEVIN.
JOHN GOODLAND, JR.
